(57) **CLAIM**

The ornamental design for a lift mechanism for an umbrella or the like, as shown and described.

DESCRIPTION

FIG. 1 shows a front view of a lift mechanism for an umbrella or the like, showing our new design;

FIG. 2 shows a rear view thereof;

FIG. 3 shows a right side view thereof;

FIG. 4 shows a left side view thereof;

FIG. 5 show a bottom view thereof; and,

FIG. 6 shows a top view thereof.

The elements shown in broken lines form no part of the claimed design.
